UNITED STATES PATENT OFFICE.

EDMUND SPENSER TIDDEMAN, OF HORNCURCH, ENGLAND, ASSIGNOR TO W. E. SYKES INTERLOCKING SIGNAL COMPANY LIMITED, OF CLAPHAM, LONDON, ENGLAND.

RAILWAY SIGNALING APPARATUS AND APPARATUS FOR STOPPING TRAINS INDEPENDENTLY OF DRIVERS.

Application filed July 24, 1920. Serial No. 398,787.

(GRANTED UNDER THE PROVISIONS OF THE ACT OF MARCH 3, 1921, 41 STAT. L., 1313.)

To all whom it may concern:

Be it known that I, EDMUND SPENSER TIDDEMAN, of Wood End, Great Nelmes, Hornchurch, in the county of Essex, England, a subject of the King of Great Britain, have invented certain new and useful Improvements in and Relating to Railway Signaling Apparatus and Apparatus for Stopping Trains Independently of Drivers (for which I have filed an application in England Feb. 19th, 1917, Patent #112,191), of which the following is a specification.

This invention relates to that class of apparatus designed on the one hand to apply the brakes of a train or railway vehicle and give a corresponding danger signal on passing a track-ramp, in both cases by mechanical means, and on the other hand to restrain the application of the brakes and indication of the danger signal, if the road is clear, by electrical means adapted to substitute a safety signal indication for that of the danger signal, the said electrical means embodying, it may be, a polarized relay serving, on single-line systems, for the purpose of discriminating between electrically energized ramps which appertain on the one hand to signals for controlling traffic in the direction wherein the train is running, and on the other hand to signals for controlling traffic in the opposite direction.

In such apparatus a lever or equivalent movable device is caused to move into an operative position and enable a danger signal to be given, or not to be given, according to whether an electromagnetic device forming part of such apparatus is dead, or is energized by a signalman completing its circuit, as for instance through an insulated ramp on the line and an insulated shoe carried by a plunger or other movable device that forms part of the apparatus and is operated by the ramp when passing over the same and controls the action of the lever or equivalent device, hereinafter referred to for brevity and distinction as the controlled lever.

A construction of signaling apparatus of the class referred to is described in the specification of former British Letters Patent No. 6499 of 1915 granted to me.

Now the present invention has for its object to adapt apparatus of the kind referred to for use on a locomotive provided with a steam brake, for the purpose of automatically applying such brake and for bringing into action a steam whistle, siren or like danger signal when this is required to be done. It also has for its object to adapt such apparatus for bringing about the operation of the air brakes or vacuum brakes on a train of vehicles attached to the locomotive provided with the steam brake apparatus.

To this end there are associated with the controlled lever of apparatus of the kind referred to, and with the cylinder of the steam brake apparatus, a steam valve on the locomotive boiler controlled by the said lever, an automatic brake valve connected to the said steam valve, to the brake cylinder, and to an exhaust pipe controlled by a valve, which may be the driver's steam brake valve, and a pipe provided with a steam whistle, siren, or equivalent audible signaling device connected to the steam valve on the delivery side thereof. The arrangement is such that when the controlled lever is permitted or caused to move, the steam valve is opened and steam admitted to the steam brake cylinder so as to apply the steam brake, and to the audible signaling device so as to give an alarm, and when the controlled lever is returned to its normal position, the steam valve is closed, the audible signal is stopped, and the automatic brake valve returned to its normal position in which it places the steam brake cylinder in communication with the exhaust pipe to allow of the brake being taken off.

In the accompanying drawings Figure 1 is an elevation, partly diagrammatic, illustrating the invention as applied for use on a locomotive provided with a steam brake, and Figure 2 is a side elevation of a portion of the mechanism shewn in Figure 1. Figure 3 is a view similar to Figure 1, illustrating the combination, with the arrangement shewn in Figure 1, of means for bringing about the operation of vacuum brakes on a train of vehicles attached to the same locomotive; Figure 4 being a sectional side ele-

vation of the air-valve which is operated directly by the controlled lever, drawn to a larger scale. Figure 5 is another view similar to Figure 1, illustrating the combination, 5 with the arrangement shewn in Figure 1, of means for bringing about the operation of air-pressure brakes on a train of vehicles attached to the locomotive.

In all the arrangements illustrated, 11 is 10 a plunger fitted to slide vertically in guides 12 carried by a plate 13 mounted upon the framing of the locomotive, the plunger tending to descend in its guides under the stress of a spring 14. The plunger 11 is in two 15 mutually overlapping sections united by bolts 15 so as to enable the effective length of the plunger to be adjusted by sliding the one section over the other; the lower section serving to carry an insulated contact-shoe 20 16 adapted to slide over an insulated ramp (not shewn) which is mounted in the permanent way and whereby the plunger as a whole is forced upwards in its guides against the tension of the spring 14. 25 17 is the controlled lever (already referred to) which is fulcrumed at 18 to the plate 13 and normally held in the position shewn in full lines in Figures 1, 3 and 4, by a projection 19 upon the lever abutting against the 30 extremity of one arm of a bell-crank trigger-lever 20 which is fulcrumed to the plunger 11 at 21 and which normally rests upon a stop 22 on the plunger, a spring 23 tending to retain the lever 20 in this position. So 35 long as the controlled lever 17, by its projection 19, abuts against the trigger-lever 20, it holds in their relatively straightened positions the limbs 24, 25 of a toggle whereof the limb 24 is pivoted to the lever 17 at 26 whilst 40 the limb 25 is pivoted to the plate 13 at 27, the middle joint 28 of the toggle being raised when the toggle as a whole is thus straightened. 29 is a counterweight carried by an 45 extension of the limb 25 and tending to straighten the toggle. 30 is the armature of an electromagnet 31, one end of whose winding is earthed whilst the other is connected to the wire leading from the shoe 16 to the electric bell or other electrically operated 50 alarm within the cab of the locomotive. The electromagnet 31 is mounted on the plate 13, whilst the armature 30 is carried by the toggle limb 25 so that, when the electromagnet 31 is energized as a result of the shoe 55 16 passing over an electrically "live" ramp, the consequent attraction of its armature 30 (assisted by the weight 29) will cause the toggle 24, 25 to be held in the straightened position and the controlled lever 17 to be 60 held in the normal position indicated in full lines on Figures 1, 3 and 5. When, as a result of the shoe 16 passing over an electrically "dead" ramp, the toggle-centre 28 is allowed to drop and the lever 17 assumes 65 the abnormal position indicated in dotted

lines, the subsequent straightening of the toggle, and consequent restoration of the controlled lever 17 to normal position, can be effected by means of a bell-crank resetting lever 32 which is fulcrumed to the plate 13 70 at 33 and controlled by a rod 34 attached to one arm of the lever 32, whereof the other arm has pivoted to it a link 35 having a pin-and-slot connection at 36 with the limb 24 of the toggle. 75

All the parts 11—36 are found in the apparatus illustrated and described in the specification of British Letters Patent No. 6499 of 1915 already referred to.

Referring now to the arrangement shewn 80 in Figure 1 of the present specification, it will be seen that the controlled lever 17, has, beyond the point 26, an upward extension 37 which is connected in the example illustrated by means of a rod 38, a bell-crank lever 39, and an adjustable wire 40, to a lever 41 fulcrumed at 42 to the casing 43 of a steam valve mounted on the boiler of the locomotive and serving to control the passage 85 of steam from the boiler to the operative cylinder (not shewn) of the steam brake of the locomotive. So long as the controlled lever 17 is in normal position, it holds the wire 40 in tension so as to cause the lever 41 to keep the steam valve closed against the 90 pressure in the boiler, but when, by the raising of the plunger 11, the trigger-lever 20 is carried upwards clear of the projection 19 on the lever 17, the latter (unless retained in normal position by the restraining action 95 of the electromagnet 31 upon the toggle 24—25) will be freed and will cease to retain the lever 41 in position to hold the steam valve closed. 100

In the example illustrated, the steam valve 105 proper is a conical valve 44 having a spindle comprising two telescopically arranged sections 45, 46 encircled by a coiled spring 47 which abuts at one end against the valve 44 on the section 45 and at the other end 110 against a second conical valve 48 on the section 46, this latter section extending through an aperture in a screw-cap 49 and bearing against the lever 41. Normally this lever 41 compresses the spring 47 so as to hold the valve 44 closed against its seat, but when said lever is released by the freeing of the lever 17 from its trigger lever 20, the pressure within the boiler causes the valve 44 to open and, by means of the spring 47, holds the valve 48 securely against a seat surrounding the section 46 of the valve spindle at the inner end of the cap 49, so that leakage of steam at this point is prevented without the use of a stuffing box and gland. 120 125

The steam valve casing 43 has a flange 49^a for attachment to the boiler, and is provided, between the seats of the valves 44 and 48, with a branch passage 50 from which two pipes 51, 52 lead, the one pipe 51 being 130

connected to a steam whistle or equivalent steam-actuated alarm (not shewn) within the cab of the locomotive, whilst the other pipe 52 leads to a valve for automatically controlling the supply and exhaust of steam to and from the operating cylinder of the locomotive steam brake. This automatic valve, in the example illustrated, comprises a cylindrical casing 53 wherein is fitted to slide 5 a piston-valve 54 normally held, at that end of the casing into which the pipe 52 opens, by a spring 55 having its abutment against a screw-plug 56 which closes the other end of the casing and is provided with a tubular 10 axial prolongation 57 serving as a guide for the stem 58 of the piston-valve 54. At a point just behind the valve 54 when the latter is in normal position, the casing 53 has a port 59 leading, by way of a pipe 60, to 15 the steam brake cylinder (not shewn), and farther towards the rear another port 61 leads, by way of a pipe 62, to the exhaust of the driver's manually controlled steam brake valve (not shewn); the valve 54, on passing 20 fully across the port 59, being arrested by the inner end of the plug-extension 57 in position to close the port 61. The arrangement is such that so long as the valve 54 is 25 in the normal position shewn, a free passage 30 is open between the pipes 60 and 62, but that when, as a result of the opening of the valve 44, steam is admitted to the pipe 52, the piston-valve 54 will be forced back in opposition to the spring 55 until the port 59 is 35 uncovered, whereupon steam passes from the pipe 52, by way of the pipe 60, to the steam brake cylinder; whereas, on the valve 44 being closed, the valve 54 is returned to 40 normal position by the spring 55 so as to permit of the steam being exhausted from the 45 brake cylinder if the driver's steam brake valve is in the appropriate position.

In operation, normally all parts occupy the positions shewn in full lines in Figure 1, and the electromagnet 31 is not energized. When the locomotive passes over the ramp on the permanent way, the plunger 11 is raised, the trigger-lever 20 is withdrawn from contact with the projection 19 and, if 50 the corresponding signal be at "line blocked" and the ramp in consequence electrically "dead", the electromagnet 31 remains de-energized, so that, the toggle-centre 28 being free to descend, the controlled lever 17, 55 yielding to the pressure transmitted from the valve 44 to the lever 41, ceases to retain this lever in position to hold the valve 44 closed against the pressure of the steam in the boiler. The result is that the steam, 60 passing by way of the valve 44 and pipe 52, forces back the piston valve 54 and thus gains access to the steam brake cylinder so as to bring about the application of the brake: steam passing at the same time through the 65 pipe 51 to the whistle in the cab. Even if

the driver should open his brake valve to exhaust, the steam brake cannot be taken off so long as the pressure of the steam through the valve 44 holds the piston-valve 54 in position to close the port 61; the valve 44 remaining open notwithstanding the descent of the plunger 11 in the event of the locomotive passing clear of the ramp on the permanent way, since the trigger-lever 20 will remain hung up on the projection 19 when the plunger carries down the stop 22. 70

In order to release the brake, the driver must reset the controlled lever 17, for which purpose he actuates the rod 34 (manually or otherwise) so as, by raising the link 35, to 80 lift the toggle-centre 28 and restore the lever 17 to normal position, wherein said lever is thereupon retained by the trigger-lever 20, which drops back upon the stop 22 into position to abut against the projection 19. 85 This restoration of the controlled lever 17 to normal position causes the lever 41 to close the valve 44, thus permitting the spring 55 to return the piston-valve 54 to normal position and reopening the communication between the steam brake cylinder and the exhaust of the driver's brake valve by way of the pipes 62 and 63. 90

If, when the locomotive passes over the ramp in the permanent way, the corresponding signal be at "line clear" and the ramp in consequence electrically "alive", the electromagnet 31 will be energized by current transmitted to it through the shoe 16 so that, although the plunger 11 will be raised as before, and the trigger lever 20 carried upwards clear of the projection 19, the toggle 24, 25 will be retained by the armature 30 in the straightened position and the controlled lever 17 will therefore remain 100 in normal position and will hold the valve 44 closed; the subsequent descent of the plunger 11, when the locomotive has passed clear of the ramp, restoring the trigger lever to its normal position of abutting 105 against the projection 19. Whilst the shoe 16 is passing over the ramp, current will be transmitted therefrom through the wires *a* which may lead to an electric bell in the cab so as to notify the driver that all is clear. 110

In the arrangement shown in Figure 3, all the mechanism described above with reference to Figure 1 is found, together with the following additional parts whereby to adapt the invention for use not only with steam brake apparatus on the locomotive itself, but also with vacuum brake apparatus on a train of vehicles attached to the same locomotive. 115

Referring now to Figures 3 and 4, it will be seen that upon the plate 13 is mounted the casing 63 of an air-valve 64 (Figure 4) for controlling the application of the vacuum brakes on the train and the giving of an alarm signal in the cab of the locomotive. 120

tive. So long as the controlled lever 17 is in normal position, the valve 64 is held closed by the action of a second arm 65 of the lever 17 which then transmits pressure, through a spring 66 coiled about the spindle 67 of the valve, to a collar 68 on the lower end of the spindle, so as to draw down the valve 64 upon its seat and shut off communication between two pipes 69 and 70 which open from the casing 63 above and below the valve-seat respectively; the pipe 69 being connected to the train vacuum pipe (not shewn) whilst the pipe 70 is connected with a syren or equivalent air-operated alarm signal (not shewn) in the cab of the locomotive.

In this case the rod 34 whereby, in the arrangement shewn in Figure 1, the resetting-lever 32 is actuated, is replaced by the piston-rod 71 of a resetting-cylinder 72 whose piston 73 is normally held by a spring 74, coiled about the rod 71, at the right hand end (Figure 3) of the cylinder. This end of the cylinder 72 is open to the atmosphere by way of an aperture 75 in the end cover, the strength of the spring 74 being made such that, on the space at the left side of the piston 73 being exhausted, the pressure of the atmosphere will overcome the stress of the spring and move the piston 73 towards the left so as to effect the resetting of the controlled lever 17. At its left-hand end the cylinder 72 communicates by way of a pipe 76 with the train vacuum-pipe, the connection being controlled by a manually-operated resetting valve. For this purpose the pipe 76 leads from the cylinder 72 to a chamber 77 within the casing of, and at one side of the seat of, the resetting-valve 79, which is under the control of the driver; the valve 79, when closed, cutting off communication between the chamber 77 and another chamber 80, at the back of the valve and within the valve-casing 78. The valve-stem 81 passes at one side of the valve through the end cover of the chamber 77 and is furnished externally with a push-knob 82; at the other side the stem 81 passes through the chamber 80 and has coiled around it a spring 83 whereby the valve 79 is normally held closed as shewn. The chamber 80 communicates by way of a pipe 84, with an auxiliary vacuum-reservoir 85 which is also connected, by way of a pipe 86, with the train vacuum-pipe; the reservoir 85 being permanently open to the pipe 84 but normally cut off from the pipe 86 by a non-return valve 87 which closes (towards the reservoir) communication between the pipe 86 and a passage 88 into which the pipe 84 and reservoir 85 both open. When the train vacuum pipe is being exhausted, the valve 87 is free to rise and permit of the exhaustion of the auxiliary vacuum reservoir 85, pipe

84, and chamber 80; the spring 83 being, however, made sufficiently strong to hold the valve 79 closed against atmospheric pressure in the chamber 77.

In operation, the locomotive steam brake is controlled as described with reference to Figure 1. When the controlled lever 17 is displaced from normal position, its arm 65 ceases to hold the valve 64 closed against the atmospheric pressure in the pipe 70, so that air is permitted to pass through and sound the syren in the cab and gain access by way of the pipe 70, valve 64, and pipe 69, to the train vacuum pipe; with the result that the vacuum brakes on the train are applied in the well-known manner. These brakes cannot be taken off so long as the controlled lever 17 remains in abnormal position, as the valve 64 continues free to open under atmospheric pressure and admit air to the train-pipe through the pipes 70 and 69.

In order to release the vacuum brakes, the driver must open the resetting-valve 79 by means of the push-knob 82: this action putting the left-hand side of the resetting-cylinder 72 in communication, through the pipes 76 and 84, with the reservoir 85, so that, a partial vacuum being produced on that side of the piston 73, the atmospheric pressure on the opposite side of the piston is able to overcome the stress of the spring 74 and, by forcing the piston 73 towards the left, actuate the resetting lever 32 so as to raise the link 35 and reset the controlled lever 17 as previously explained with reference to Figure 1. The resetting of the lever 17 also enables the steam brake on the locomotive to be taken off, as already explained.

In the arrangement shewn in Figure 5, all the mechanism described above with reference to Figure 1 is found, together with the following additional parts whereby to adapt the invention for use not only with steam brake apparatus on the locomotive itself, but also with air-pressure brake apparatus on a train of vehicles attached to the same locomotive.

Referring now to Figure 5, it will be seen that upon the plate 13 is mounted the casing 89 of an air-valve 90 for controlling the application of the air-pressure brakes on the train and the giving of an alarm signal in the cab of the locomotive. So long as the controlled lever 17 is in normal position, the valve 90 is held closed by said lever. This valve is constructed somewhat similarly to the valve 44: that is to say, the air-valve proper is a conical valve 90 having a spindle comprising two telescopically arranged sections 91, 92 encircled by a coiled spring 93 which abuts at one end against the valve 90 on the section 91 and at the other end against a second conical valve 94 on the section 92; this latter section extending

through an aperture in a screw-cap 95 and bearing against the lever 17. The valve 90 controls communication between the interior of the casing 89 and a pipe 96 connected 5 with the train air-pipe (not shewn) whilst the casing 89 is provided, between the seats of the valves 90 and 94, with the branch passage from which a pipe 97 leads to a whistle or equivalent alarm (not shewn) within

10 the cab. Normally the lever 17 compresses the spring 93 so as to hold the valve 90 closed against its seat, but when said lever is released as described with reference to Figure 1, the air pressure within the pipe 15 96 causes the valve 90 to open and, by means of the spring 93, holds the valve 94 securely against a seat surrounding the section 92 of the valve-spindle at the inner end of the cap 95, so that leakage of compressed air at 20 this point is prevented without the use of a stuffing-box and gland, the entire volume of air which escapes from the pipe 96 being thus available for blowing the alarm whistle.

25 In this case the rod 34 whereby in the arrangement shewn in Figure 1 the resetting-lever 32 is actuated, is replaced by the piston-rod 98 of a resetting cylinder 99 whose piston 100 is normally held by a spring 101, coiled about the rod 98, at the right-hand end of the cylinder. This end of the cylinder 99 communicates, by way of a pipe 102, with the main air-pressure reservoir of the locomotive, the connection being controlled 30 35 by a manually-operated resetting-valve constructed similarly to the resetting-valve described with reference to Figure 3. For this purpose the pipe 102 leads from the cylinder 99 to a chamber 103 within the casing of, and at one side of the seat of, the resetting valve 40 45 104, which is under the control of the driver; the valve 104, when closed, cutting off communication between the chamber 103 and another chamber 105, at the back of the valve and within the valve-casing 106. The

50 valve-stem 107 passes at one side of the valve through the end cover of the chamber 103 and is furnished externally with a push-knob 108: at the other side the stem 107 passes through the chamber 105 and has coiled around it a spring 109 whereby the valve 104 is normally held closed as shewn. The chamber 105 communicates, by way of a pipe 110, with the main air-pressure reservoir (not 55 shewn).

55 In operation, the locomotive steam brake is controlled as described with reference to Figure 1. When the controlled lever 17 is displaced from normal position, it ceases to 60 hold the valve 90 closed against the air-pressure in the pipe 96, so that compressed air is permitted to escape from the train air-pipe through the pipes 96 and 97 and the whistle on the latter, thus sounding the alarm in the cab, whilst the escape of this air at the same

time brings about the application of the air-pressure brakes on the train in the well-known manner. These brakes cannot be taken off so long as the controlled lever 17 remains in abnormal position, as any air-pressure within the train-pipe is free to escape to the atmosphere by the pipes 96 and 97. 70

In order to release the air-pressure brakes, the driver must open the resetting valve 104 75 by means of the push-knob 108; this action admitting compressed air from the main reservoir, through the pipes 110 and 102, to the resetting-cylinder 99, with the result that the stress of the spring 101 is overcome 80 and, the piston 100 being forced towards the left, the resetting-lever 32 is actuated so as to raise the link 35 and reset the controlled lever 17 as previously explained with reference to Figure 1. The resetting of the lever 17 also enables the steam brake on the locomotive to be taken off, as already explained. 85

It will be obvious that both vacuum-brake control apparatus as described with reference to Figure 3, and also air-pressure brake control apparatus as described with reference to Figure 5, can be fitted in combination with steam brake control apparatus as described with reference to Figure 1. 90 95

It is to be observed that failure of any portion of the apparatus will result in the alarm signal being given in the cab of the locomotive.

The system is interchangeable with other systems which employ fixed electrically energized ramps, provided the latter are mounted in the same relative position on the permanent way. 100

The details of apparatus constructed according to the present invention may be varied to suit particular requirements, the examples shewn in the drawings being given merely as illustrating convenient embodiments of the invention. 105 110

Having now particularly described and ascertained the nature of my said invention and in what manner the same is to be performed, I declare that what I claim is:—

1. In apparatus for automatically applying the brakes of a railway train or vehicle, and coincidentally actuating an alarm signal in the locomotive cab, the combination of a steam valve connected with the boiler of the locomotive, a controlled lever arranged to normally maintain said steam valve in its closed position, an automatic valve casing connected with the outlet end of said steam valve, a first connection from said automatic valve casing to the steam brake system of the locomotive, a second connection from said automatic valve casing to the exhaust of the engine driver's brake valve, an automatic valve in said automatic valve casing for alternately controlling the 115 120 125 130

communication between said first and second connections and the connection from said automatic valve casing to said steam valve, a connection from the outlet side of the latter to a signaling device in the locomotive cab and means for restoring the controlled lever to normal position.

2. In apparatus for automatically applying the brakes of a railway train or vehicle and coincidentally actuating an alarm signal in the locomotive cab, the combination of a steam valve connected with the boiler of the locomotive, a controlled lever arranged to normally maintain said steam valve in its closed position, an automatic valve casing connected with the outlet end of said steam valve, a first connection from said automatic valve casing to the steam brake system of the locomotive, a second connection from said automatic valve casing to the exhaust of the engine driver's brake valve, an automatic valve in said automatic valve casing for alternately controlling the communication between said first and second connections and the connection from said automatic valve casing to said steam valve, a connection extending from the vacuum brake system of the train to a pneumatically operated signaling device located in the locomotive cab, a valve controlling said connection normally maintained in its closed position by said controlled lever, means for restoring the latter to its normal position, an auxiliary vacuum reservoir, a resetting cylinder connected with said auxiliary vacuum reservoir, a piston movable in said cylinder and connected with said restoring means, and a normally closed, manually operated valve in the connection between the resetting cylinder and the auxiliary vacuum reservoir, and controlling communication between the latter and said cylinder whereby said piston is operated by atmospheric pressure when said cylinder is in open communication with said auxiliary vacuum reservoir.

3. In apparatus for automatically applying the brakes of a railway train or vehicle and coincidentally actuating an alarm signal in the locomotive cab, the combination of a

steam valve connected with the boiler of the locomotive, a controlled lever arranged to normally maintain said steam valve in its closed position, an automatic valve casing connected with the outlet end of said steam valve, a first connection from said automatic valve casing to the steam brake system of the locomotive, a second connection from said automatic valve casing to the exhaust of the engine driver's brake valve, an automatic valve in said automatic valve casing for alternately controlling the communication between said first and second connections and the connection from said automatic valve casing to said steam valve, a connection extending from the air brake system of the train to a pneumatically operated signaling device located in the locomotive cab, a valve controlling said connection normally maintained in its closed position by said controlled lever, means for restoring the latter to its normal position, a resetting cylinder connected with said air brake system, a piston movable in said cylinder and connected with said restoring means and a normally closed, manually operated valve in the connection between the resetting cylinder and the air brake system and controlling the operation of said resetting piston.

4. In apparatus for automatically applying the brakes of a railway train or vehicle and coincidentally actuating an alarm signal in the locomotive cab, the combination of an automatic valve connected with the boiler of the locomotive, a connection from said boiler connection to a signaling device in the locomotive cab, a plurality of connections leading from said automatic valve, means for controlling the operation of the latter to alternately cause one of said connections to communicate with the boiler connection and to coincidentally open the alarm connection or to bring said plurality of connections into communication with each other, pneumatically operated means for restoring said controlling means to its normal position and a manually operated valve for controlling the operation of said pneumatically operated means.

EDMUND SPENSER TIDDEMAN.
